CALCULATING MACHINE WITH
POLARIZED RELAYS

Walter Hoppe, Bern, Switzerland, assignor to El-Re-Ma
S.A. per lo sfruttamento di brevetti, Lugano, Switzerland,
a corporation of Switzerland

Filed July 22, 1954, Ser. No. 445,069

Claims priority, application Switzerland July 31, 1953
25 Claims. (Cl. 235—159)

This invention relates to electrical calculating machines.

More particularly the invention concerns an electrical calculating machine controlled by current impulses, comprising at least three groups of contacts for introducing into the machine the numbers involved in an operation and for performing that operation, and a group of controls determining the kind of operation to be performed.

Such calculating machines are already known, but they are generally too cumbersome and too heavy to be portable, because of the considerable number of relays they comprise.

It is an object of the calculating machine with which the invention deals to correct this drawback; it differs from previously-known machines in that the contacts of at least one of these groups are controlled by polarized relays with at least three positions, one of these positions being the rest position, these relays making it possible to perform certain operations by reversing the direction of the current impulse acting on the said group. This characteristic makes it possible to save contact-makers and switching elements, and to simplify the calculation diagrams and their control mechanisms, as compared with machines hitherto known.

It is desirable to use relays with windings for electro-magnetically polarizing their armatures; this makes it possible to choose the direction of polarization at will so as to perform certain control procedures.

It is preferable to choose the value of the polarization windings and the air-gaps of the said elements in such a way that the armatures when attracted are kept in the attracted position by the polarization action alone, even when the main winding is no longer excited, until the polarization is cut off. The elements used are thus self-locking, without providing special electrical or mechanical locking devices.

It is well known that the possibility of locking contact-making elements is of basic importance for the construction of machines of the above type. Locking of the said elements in several positions by the polarization windings has still other advantages, as it takes place without inertia, since no other mechanical part, neither a bolt nor anything else, is actuated. Actually, movement during calculating operations is confined to the movements of light armatures moving a fraction of a millimeter; this allows great speed of calculation to be attained.

The following description indicates, by way of example and with reference to the subjoined drawings, several embodiments of a calculating machine according to the invention.

FIGS. 1 to 9a represent various relays and groups of switching elements that can be used in the said machine.

FIG. 10 schematically illustrates a calculation circuit that makes it possible to perform the addition of the numbers defined in the A and B groups, the result of which is determined by the contacts of the R group.

FIG. 11 shows schematically a transfer circuit that makes it possible to transfer the result in the R group to the B group.

FIG. 12 illustrates the principle of converting a number into its nine's complement.

2

FIG. 13 is a diagram of the current impulses whose purpose it is to actuate relays.

FIG. 14 schematically represents a rotary commutator for producing the impulses of FIG. 13.

FIG. 15 shows, very schematically, how the calculating and transfer circuits are fed by an impulse generator Ig.

FIG. 16 schematically represents the principal circuits of the machine.

FIGS. 17 to 20 illustrate the principle of ordering the operations.

FIG. 21 shows another impulse diagram that can be used to actuate the relays of the various circuits.

FIGS. 22 and 23 represent an impulse generator for producing the impulses of FIG. 21.

FIGS. 24, 25 and 26 represent the calculation and transfer circuits of another embodiment of the machine, in which the representation of the numbers is made on the decimal system.

FIGS. 27, 28, 29, and 30 refer to a variant of the calculation and transfer circuits in which the representation of the numbers is made on the odd-even system.

The relay shown in FIG. 1 comprises a magnetic core 1 bearing a control winding 5, and two armatures 2 and 2a that are urged against blocks 6 and 6a by springs 7 and 7a. Input conductors 8 and 8a in the form of wires or flexible strips are connected to these armatures, while a third input conductor 9 is connected to the core. The poles of armatures 2 and 2a, which are U-shaped, plunge into polarization coils 10, 11 and 10a, 11a respectively and are polarized by the latter. The ampere-turns of these polarization coils are so chosen that when the effect of a polarization coil is opposed to that of the control coil, the resultant magnetic field is not sufficient to cause the attraction of an armature subjected to this field.

When a current is sent to control coil 5, for example, so that core 1 has its south magnetic pole up and its north magnetic pole down, armature 2 is attracted while armature 2a is not for the upper end of armature 2 has been polarized to show a north magnetic pole, while the upper end of armature 2a has been polarized to show a south magnetic pole at its upper end. If the direction of the current is reversed, either in polarization coils 10, 11, 10a and 11a, or in main coil 5, armature 2a is attracted. The armatures make the electric contact at their two ends, in two points, which increases the certainty of this contact's functioning. The contact points of the armatures are coated with a non-magnetic metal which is a good conductor, such as silver or copper, in order to assure a good electrical contact and to diminish the remanence of the magnetic circuit. This relay forms a switching element that can have the following three positions:

0: armatures 2 and 2a are not attracted (no current in main coil). Input conductor 9 is not connected to 8 and 8a.

1: armature 2 is attracted, 9 is connected to 8.

II: armature 2a is attracted, 9 is connected to 8a.

If the intensity of the current in the windings, the maximum gap between core 1 and armatures 2 and 2a, and the thickness of the non-magnetic metal coating on

the contact points are correctly determined, the armature that has been attracted, 2 or 2a as the case may be, can be maintained in its position, after the excitation of coil 5 has been broken, by the action of polarization coils 10 and 11, or 10a and 11a, respectively. When the current is broken in the polarization coils, the attracted armatures are brought back to rest position by springs 7 and 7a.

FIG. 2 represents a group made up of five relays of the same kind as those shown in FIG. 1, except that in them each control coil 5 surrounds two parallel cores 1 that are magnetically and electrically insulated from each other. Each of these cores cooperates with two arma-

tures 2 and 2a. In this case it is convenient to have parts 32 of insulating material to support these elements and at the same time form the body of polarization coils 10, 11, 10a and 11a of the armatures. The armatures 2a and the polarization coils 10a and 11a are not shown in the drawing.

In the assembly shown, a common coil 11 is shown surrounding the lower end of the armatures 2 of the five elements and another common coil 10 surrounding the upper end of these armatures.

The relay shown in FIG. 3 has a core 1 surrounded by a control coil 5. Polarization coils 10 and 10a are mounted on studs 12 and 12a, which are separated from the core by insulating layers 13 and 13a and bear parts 14 and 14a, on which armatures 2 and 2a are fastened by means of flat springs 15 and 15a. A part 16 made of insulating material serves as a stop for the armatures and makes it possible to set the maximum air-gap between the latter and the core.

Excitation of polarization coils 10 and 10a polarizes the armatures, and when the current flows through control coil 5, armature 2 or 2a is attracted, according to the direction of the polarization.

It is obvious that several relays like the one in FIG. 3 could be combined to make an assembly of the same sort as the one in FIG. 2.

The combination of magnetic circuits and electrical contacts, as shown in the preceding illustrations, has advantages for the construction of the relays, but still is not indispensable.

FIGS. 4 and 5 illustrate a relay of the same type as the one in FIG. 3, but with an added feature, a means for showing the position of an armature. The core 1 of this relay is longer and a lever 27 is attached to its end on an axis 28 around which it can rotate. A spring 29 urges this lever against a movable stop 30 that can be shifted in the direction of arrow 31. When this stop 30 is shifted in this direction, spring 29 causes lever 27 to rotate; the lower end of lever 27 then comes between armature 2 and core 1. If armature 2 is in attracted position, that is, in contact with core 1, when stop 30 is shifted, the lower end of lever 27 strikes against armature 2 and this lever remains in the position shown in FIG. 4, instead of being able to put itself in alignment with core 1. The upper end of the said lever thus describes a path that is much longer than the displacement of an armature; this permits the use of a simple apparatus for mechanically exploring the relays whose armatures are attracted, without requiring very close machining tolerances.

The relays described above suffice for the construction of a calculating machine according to the invention. However, in the embodiment described below, use will also be made of multiple-contact mechanical wipers; an example of their construction is shown in FIGS. 6 and 7.

In general, these wipers comprise a group of movable points moving across fixed points and, because of the friction of these points against each other due to the pressure required to insure a good electrical contact, a considerable force is required for shifting the movable points. To avoid this drawback, it is preferable to have wipers whose points are not in contact during their respective movements, the contact pressure between fixed and movable points occurring only after the latter have moved into position. Wipers of this kind, in which the movable and immovable points are made of a magnetic material and enter into magnetic circuits that can be excited by means of a winding, are described in detail in application No. 356,577, now Pat. No. 2,854,541.

On a sliding part 70 of insulating material (FIG. 6), which is attached to rods 71 and 72, there are armatures 73, set in channels in which they can make a small movement. This movement is limited on one side by rods 74 and 75 and on the other by magnetic cores 76. The latter are insulated from each other by insulating layers 77 and are surrounded by a winding 78. So long as the

latter is not excited, part 70, bearing armatures 73, can be moved virtually without friction, and, depending on the number of armatures 73 and cores 76, can assume a certain number of positions for which each armature 73 is opposite a core 76.

When coil 78 is energized for one of these positions, armatures 73 are attracted to cores 76 and exert a considerable pressure on them at two points of contact 79 and 80. Since these cores 76 constitute the fixed points and the armatures the movable points, a stable and certain electrical contact is obtained in this way, because of this contact at two points. It is advisable to cover these cores 76 and the armatures with a layer of precious metal in order to improve the electrical contact.

FIG. 8 is a view of a variant of a relay according to FIG. 3, in which, however, polarization windings 10 and 10a have been placed close to the free ends of armatures 2 and 2a.

FIGS. 9 and 9a represent an assembly made up of five relays like the one in FIG. 8, in a similar way to FIG. 2. In this case, however, the polarization coils have been so arranged that every relay can assume five positions 0, I, II, III, IV, the 0 position being the rest position, in which no electrical contact is made.

As is seen from FIG. 9a, connecting the polarization coils in a suitable manner makes it possible to polarize three armatures of a group of four in one sense and the fourth in the other sense, so that by sending through a control current with a suitable polarity we can selectively bring about the attraction of a single armature out of the group of four.

The five relays of this set each have a core 56, 57, 58, 59 and 60 passing through main windings 34, 35, 36, 37 and 38 respectively. Each core is designed to cooperate with four armatures capable of entering into contact with it. Core 57 cooperates with armatures 33a, 33b, 33c, 33d, which are polarized by four coils 42, 42a, 43 and 43a. If polarization coils 41 to 46 as well as 41a, 43a, 45a are connected in the same direction, while coils 42a, 44a, 46a are connected in the opposite direction, and a current is sent through control coil 35 only, its direction being so chosen that only those armatures that are polarized by coils 42a, 44a, 46a are attracted, armature 33b will be attracted when the control coil is excited. By varying the connections and the current direction in the polarization coils, the attraction, as desired, of any of the four armatures 33a, 33b, 33c, 33d can be obtained.

Electrical calculation portion

FIG. 10 schematically represents a calculating circuit that makes it possible to perform the addition of the numbers defined in the A and B groups, the result of which is defined by the contacts of the R group.

FIG. 11 shows schematically a transfer circuit that makes it possible to transfer the result in the R group to the B group.

FIG. 12 illustrates the principle of converting a number into its nine's complement.

The calculating machine described below comprises three groups of contacts A, B and R. The A group is made up of multiple-contact wipers such as in FIG. 6, while the contacts of the B and R groups are controlled by polarized relays with at least three positions such as in FIGS. 1, 3 and 8. The contacts of each group are capable of defining a number by their closed positions. The wiper and relay contacts of the respective A and B groups are connected to the control windings of the relays of the R group in such a way as to cause the closure of those contacts of the R group that define the number corresponding to the addition of the number defined by the contacts of the A and B groups. The contacts of the R group are connected to the control windings 5 of the relays of the B group in such a way as to cause the closure of those contacts of the B group that define a number that will be a function of the number defined in the

R group, that is, the number itself or its nine's complement.

The operation of the various calculating machines that will be described hereinafter has been so devised that the positions of the contacts of the A group remain the same throughout a calculation, as is indicated in detail in application No. 445,070.

In principle, a calculation consists of a series of two-phase elementary operations. Each two-phase elementary operation itself is made up of a calculation phase and a transfer phase, the calculation phase being that in which the numbers defined in the A and B groups, whose result is defined in the R group, are added, while the transfer phase is that during which the result defined in the R group is transferred to the B group.

Calculation and transfer phases

In order to make the diagrams clearer and get shorter connections, the contacts and control coils of the relays have been separated in the drawings, as is customary practice in telecommunication diagrams. It is to be noted particularly that the contacts and coils that are connected to each other never belong to the same group of relays. The circuits that make it possible to perform a calculating phase will henceforth be designated as "R circuit," while those that make the transfer phases possible will be designated as "B circuit." The control coils of the relays of the R group will be designated, for the purposes of the description, by R_i , where the index i represents the digit defined by the relay in question. When a relay can define several digits, one of them is chosen for the index i . A relay generally has two and sometimes three control coils, which are then designated as $1R_i$, $2R_i$, etc. The contacts of the relays of the R group are designated in the same manner, but with an r instead of an R for their I position and an r^* for their II position, these positions having been defined in connection with FIG. 1. One of the directions of the windings of the control coils has not been explicitly designated on the drawing, while the opposite direction is indicated by an arrow parallel to the symbol of the coil represented. In the diagrams reference signs are indicated for only one denomination order, as the signs for the other denomination orders are subject to the same rules. When the description must indicate that the relay in question is in a given denomination row, an index k is added (R_{ik} , r_{ik}), which refers to the number of the denomination row. The designation 2R23, for example, refers to the second control winding of a relay of the R group, that defines the figure 2 in the third denomination row. 2R2, on the contrary, refers to the second control coil of the relay defining the figure 2, without specifying the denomination row. The designation of the index k is omitted for the reference signs of the drawing in order to make it clearer, the indication of the denomination rows being given generally by a brace for each place. This applies equally for the designation of contacts. In addition, when a relay has only one contact or one winding, the reference will be simplified by omitting the first figure. A single contact, for example, will be designated by ri instead of $1ri$.

The control coils and contacts of the B group are designated in the same manner, except that they have the letters B and b instead of the letters R and r . The relays of the B group thus have contacts $1bi$, $2bi$ and $1bi^*$, $2bi^*$ respectively for each of the positions I and II.

In the calculating machine, whose calculation and transfer circuits are shown in FIGS. 10 and 11, the figures are defined within each decimal place by the closure of contacts on the biquinary system. In other words, seven contacts must be available to define a figure ranging from 0 to 9. Five of these contacts enable us to define the figures ranging from 0 to 4, while the two other contacts are provided to determine whether a zero or a five should be added to the figure determined by one of the first five contacts. Thus in the R group, these

first five contacts and the windings of the relays that control them, will bear an index from 0 to 4, while the indices u and v are provided for the other two contacts. The figures of a denomination row will thus be defined, on the biquinary code, by the closure of contacts whose indices are given in the table below:

	Digit	index	index
10	0-----	0	u
	1-----	1	u
	2-----	2	u
	3-----	3	u
	4-----	4	u
	5-----	0	v
15	6-----	1	v
	7-----	2	v
	8-----	3	v
	9-----	4	v

Hence, a number is always determined by the simultaneous closure of two contacts for each denomination row, both in the contacts of the A group and in those of the B and R groups, as described in application Serial No. 445,119.

The calculation circuit represented in FIG. 10 is that of a simplified calculating machine with six denomination rows in all. In this diagram, as in that of FIG. 11, only the circuits of the relay control coils have been shown, the polarization circuits being omitted. The elements belonging to each denomination row are indicated by a brace numbered from 1 to 6. The units denomination row has number one, the tens place number 2, etc. To simplify the diagrams, the reference signs have not been indicated except for one or two of the denomination rows.

FIG. 12 illustrates schematically the contacts of the B group that are needed to define on the biquinary system the various digits of a denomination row, that is, the digits from zero to nine. These contacts are controlled by four relays with one, two or three control windings and polarization windings, the latter not being shown.

The first relay has a control winding B2 and four contacts $1b2$, $2b2$, $1b2^*$ and $2b2^*$. The two contacts $1b2$ and $2b2$ constitute a double contact that closes for position I, that is, for a particular direction of the current in winding B2, while contacts $1b2^*$ and $2b2^*$ close when the direction of the current is reversed, that is, for position II.

As is seen, contacts $1b2$ and $1b2^*$, and $2b2$ and $2b2^*$, respectively, are interconnected in such a way as to set up the same connection whatever the direction of the current is in B2.

The second relay has two windings $1B1$ and $2B1$ wound in opposite directions and ordering two double contacts $1b1$, $2b1$ or $1b1^*$, $2b1^*$, respectively. The third relay has three windings $1B0$, $2B0$, $3B0$ to control two double contacts $1b0$, $2b0$, or $1b0^*$, $2b0^*$, respectively. The fourth relay is like the third, but the index 0 is replaced by u .

The digits of a denomination row are defined by the closure of these contacts according to the table below:

	Digits	contacts	contacts
60	0-----	$1bu$, $2bu$ -----	$1b0$, $2b0$ -----
	1-----	$1bu$, $2bu$ -----	$1b1$, $2b1$ -----
	2-----	$1bu$, $2bu$ -----	$1b2$, $2b2$ or $1b2^*$, $2b2^*$ -----
	3-----	$1bu$, $2bu$ -----	$1b1^*$, $2b1^*$ -----
	4-----	$1bu$, $2bu$ -----	$1b0^*$, $2b0^*$ -----
	5-----	$1bu^*$, $2bu^*$ -----	$1b0$, $2b0$ -----
65	6-----	$1bu^*$, $2bu^*$ -----	$1b1$, $2b1$ -----
	7-----	$1bu^*$, $2bu^*$ -----	$1b2$, $2b2$ or $1b2^*$, $2b2^*$ -----
	8-----	$1bu^*$, $2bu^*$ -----	$1b1^*$, $2b1^*$ -----
	9-----	$1bu^*$, $2bu^*$ -----	$1b0^*$, $2b0^*$ -----

It will be seen that the ten digits of a denomination row can be defined by a set of four relays, of which two always function simultaneously. Thus, the number of relays provided for each denomination row of the B group is equal to half the number of positions necessary to define all the digits of a denomination row, rounded out to the next higher whole number. The relation, as indicated above,

between the making of the contacts and the number that is defined makes it possible to convert very simply to the nine's complement. For, the said relays are polarized and show three positions, as has already been explained, to wit: a rest position 0, a position I for which contacts b_i are closed and a position II for which contacts b_i^* are closed. If contacts b_i or b_i^* , respectively, of a relay are closed for a given direction of the control and polarization currents, the direction of one of these currents need only be reversed for contacts b_i^* to be closed instead of b_i , or contacts b_i instead of b_i^* , as the case may be. Referring to the table above, it will be seen that reversing the direction of a current in the relays of the B group suffices to cause the closure of the contacts defining, not the number transmitted, but its nine's complement. It will be seen, for example, that the number 3 is defined by the closure of contacts $1bu$, $2bu$ and $1b1^*$, $2b1^*$. If the direction of the control current, for example, is reversed, that will bring about the closure of contacts $1bu^*$, $2bu^*$ and $1b1$, $2b1$, which define the number 6. We have thus carried out, for this denomination row, the subtraction $9-3=6$. The rest of the description will show that this possibility has many advantages and is made use of to make calculating operations possible.

Two of the four relays have a third control winding $3B0$ or $3Bu$, respectively. These windings are provided to make it possible to introduce the number zero by means of an independent control circuit. By reversing the direction of the current in these supplementary windings, those contacts may also be made to close that define the number nine instead of zero.

Referring again to FIG. 10, the calculation circuit has two input conductors ge and $ge1$, which are connected to five double contacts $1b0$, $2b0$, $1b1$, $2b1$, $1b2$, $2b2$, $1b1^*$, $2b1^*$, $1b0^*$, $2b0^*$. These contacts correspond to those represented in FIG. 12, but contacts $1b2^*$ and $2b2^*$, which are connected in parallel to contacts $1b2$ and $2b2$, have not been shown in order to avoid overcrowding the drawing. These contacts of the B group are connected to six movable points $1am$, $2am$ . . . $6am$ of a multiple-contact wiper. These six movable points can be shifted with respect to ten fixed points $1af$, $2af$ . . . $10af$, which are connected to windings $1R0$, $1R1$, $1R2$, $1R3$, $1R4$, $2R0$, $2R1$, $2R2$, $2R3$, $2R4$, respectively, of five relays of the R group. These windings are mounted two on a relay. Thus, $1R0$ and $2R0$ belong to a single relay; likewise for $1R1$ and $2R1$, $1R2$ and $2R2$, etc. The above-mentioned contacts of the B group can define a digit from 0 to 4. The movable points of the multiple-contact wiper can also assume five different positions with respect to the fixed points, so as to define the digits from 0 to 4.

The totality of these contacts of the A and B groups makes up an addition circuit, so that a current entering at ge goes only through that control winding of relay R that corresponds to the result of the addition of the numbers defined by the contacts of the A and B groups. In the first denomination row double contact $1b1^*$, $2b1^*$ is closed and defines the digit 3, while the movable points of the multiple-contact wiper are shifted two positions up and define the digit 2. If a current is sent through input conductor ge , it will go through winding $2R0$ after passing through contact $1b1^*$ and the multiple-contact wiper. Winding $2R0$ enables us to define the digit 0 or the digit 5 in the R group, according to the positions of relays Ru and Rv , which are connected in series in the same denomination row. That is, windings $1R0$ and $2R4$ form two groups ending in two output conductors. Windings $1R0$ to $1R4$ are connected to one of these output conductors and windings $2R0$ to $2R4$ to the other. These two output conductors are connected to two double contacts $1bu$, $2bu$ or $1bu^*$, $2bu^*$, respectively, that have been described in connection with FIG. 12. These contacts are connected to a multiple-contact wiper having three movable points $1amu$, $2amu$, $3amu$, capable of assuming two positions with respect to four fixed points $1afu$, $2afu$, $3afu$, $4afu$.

These fixed points are connected to four windings $1Ru$, $2Ru$, $1Rv$ and $2Rv$ of two relays Ru and Rv . This calculation circuit offers two output conductors for this denomination row. Windings $1Ru$ and $1Rv$ are connected to one of these output leads and windings $2Ru$ and $2Rv$ to the other.

A current passes through winding $1Ru$ when the result of the digits in this denomination row defined in groups A and B is less than five. When this result is between 5 and 9, the current passes through $1Rv$. When the result of this addition is at least equal to ten, the current leaves the first denomination row by the other output conductor, passing through $2Ru$ if the result is between 10 and 14 and through $2Rv$ if the result is between 15 and 19.

When the current enters through $ge1$, the result indicated by relays R is increased by a unity compared to the result of the addition of the numbers defined by the contacts of the A and B groups.

Decimal places 2 and 3 are identical with the first denomination row and the two input conductors of a denomination row are connected to the two output conductors of the preceding denomination row. Decimal places 4, 5 and 6 are analogous to decimal places 1, 2 and 3, but only have contacts of the B group, no multiple-contact wiper (group A) being provided for these denomination rows, since the keyboard of the machine has only three columns. The relays R of decimal places 4, 5 and 6 have only one main winding, however, with the exception of relays $R0$ and Ru , each of which has two windings, $1R0$ and $2R0$, or $1Ru$, $2Ru$, respectively. This simplification is due to the fact that the largest figure that can occur in a denomination row is equal to 10 (that is, 9 plus a carry), since no $A+B$ additions occur in these decimal places. The windings that only serve to define numbers greater than 10 would therefore be superfluous and have been eliminated. All the decimal places are connected in series, one after the other, so that the current entering through ge or $ge1$ goes through all of them before leaving by ga . If the sum of the two numbers defined by groups A and B in a denomination row is smaller or larger than ten, the current leaves by one or the other of the output conductors of this decimal place, producing or not producing a supplementary addition of a 1 in the following denomination row, accordingly.

As the current goes through the windings of certain relays of the R group, as indicated above, it causes the closure of the contacts of those relays that are part of the transfer circuit represented in FIG. 11. Each relay of the R group has two contacts ri and ri^* that allow the current to be sent through the windings of certain relays of the B group. Dependent on the direction of the current during the calculation phase, that is, of the current going through the calculation circuit of FIG. 10, the windings of relays R will be traversed in one direction or the other and cause the closure of contacts ri or contacts ri^* . Referring to FIG. 11, it is seen that the contacts ri of a denomination row are connected to the control windings of the relays B of the same denomination row; on the other hand, contacts ri^* of a denomination row are connected to the control windings of the relays B of the following decimal place.

Contacts ri or ri^* , respectively, of a denomination row are connected to relays B of the same denomination row or the following denomination row, respectively, so as to send the current, during a transfer phase, through the windings of those relays B that define the same number as the R relays.

By reversing the direction of the current during the transfer phase, that is, by having it enter at fa and leave by fe , those contacts of the B group are made to close that define the nine's complement of the number defined by the contacts of the R group. Finally, the transfer circuit has an independent second circuit with an input conductor $f0e$ and an output conductor $f0a$ and comprising all the windings $3B0$ and $3Bu$. If, instead of having the cur-

rent go through fe and fa , it is made to go through $f0e$ and $f0a$, a zero or a nine is introduced into each decimal place of the B group, depending on the polarity of the current.

The different operating possibilities of the circuits according to FIGS. 10 and 11 are summed up as follows:

Sending a current through the calculation circuit of FIG. 10 effects a calculation phase. The addition of the numbers defined in the A and B groups is carried out, and if the current is sent through ge instead of ge , a 1 is added to this sum at the same time. According to the direction of the current during this calculating phase, that is, according to whether the current goes from ge to ga or contrariwise from ga to ge , contacts ri or ri^* are closed. This makes it possible to transfer this result to the contacts of the B group by sending a current through fe , fa . This transfer takes place without change of denomination row if it is the contacts ri that are closed, or contrariwise with a shift to the next denomination row if it is the contacts ri^* that are closed. If the current passes from fe to fa during the transfer phase, those contacts of the B group are closed that define the same number as the one that is in the R group; if the current goes from fa to fe , those contacts of the B group are closed that define the nine's complement of the number in the R group. Finally, if the current is sent through $f0e$ and $f0a$ during the transfer phase, the figure zero or the figure nine is introduced, according to the direction of the current, in each denomination row of the B group. These different possibilities are enough to make it possible to carry out the four fundamental operations, namely addition, subtraction, multiplication and division, by means of a series of calculation and transfer phases, as is explained in detail in application No. 445,070. In what follows the name "elementary two-phase operation" or, more briefly, "elementary operation" will be given to the operation consisting of a calculation phase and a transfer phase.

Example of an electrical elementary two-phase operation

The operation

$$A+B=R$$

$$R \rightarrow B$$

(addition of the numbers A and B and cyclical transfer of the result obtained with a decimal shift to the left) will be explained in the following example, which corresponds to FIGS. 10 and 11.

$$000862 + 852828 = 853690$$

$$853690 \rightarrow 536908$$

The following numbers are set up in the wipers of the A group (biquinary code):

Five-position wipers	Two-position wipers
2	and
1	and
3	and

$u=2$
 $v=6$
 $v=8$

In the B group, the following numbers are defined and maintained by sending the current through the polarization coils:

1b11*	2b11*	1bu1*	2bu1*	8
1b22	2b22	1bu2	2bu2	2
1b13*	2b13*	1bu3*	2bu3*	8
1b24	2b24	1bu4	2bu4	2
1b05	2b05	1bu5*	2bu5*	5
1b16*	2b16*	1bu6*	2bu6*	8

During the calculation phase the direction of the control current in the R group is opposite to the direction of the

75

polarization current, in order to make ready a decimal shift to the left. This current passes through:

5       $ge \quad 1b11^* \quad 2R01 \quad 2bu1^* \quad 2Ru1 \quad 2b22$
 $1R42 \quad 1bu2 \quad 1Rv2 \quad 1b13^* \quad 2R13 \quad 2bu3^*$
 $2Rv3 \quad 2S1 \quad 2b24 \quad 1R34 \quad 1bu4 \quad 1Ru4 \quad 1b05$
 $1R05 \quad 1bu5^* \quad 1Rv5 \quad 1b16^* \quad 1R36 \quad 1bu6^*$
 $1Rv6 \quad Dga$

and closes contacts

10      $r01^* \quad ru1^* \quad r42^* \quad rv2^* \quad r13^* \quad rv3^* \quad r34^*$
 $ru4^* \quad r05 \quad rv5^* \quad r36^* \quad rv3^*$

which correspond to the digits 0, 9, 6, 3, 5, 8 (beginning with the units). Finally, the control current is shut off, but the contacts remain closed under the effect of the polarization current. On the other hand, the polarization too is cut off in the B group, which brings about the opening of the contacts that define the digits 8, 2, 8, 2, 5, 8. The machine is thus ready for the transfer phase.

During the transfer phase (FIG. 11) the direction of the control current in the B group is the same as that of the polarization current, in order to obtain a transfer without the formation of complements. This current passes through

25      $fe \quad r34^* \quad 2B15 \quad ru4^* \quad 1Bu5 \quad r05^* \quad 1B06$
 $rv5^* \quad 2Bu6 \quad r36^* \quad 2B11 \quad rv6^* \quad 2Bu1 \quad r01^*$
 $1B02 \quad ru1^*$
 $1Bu2 \quad r42^* \quad 2B03 \quad rv2^* \quad 2Bu3 \quad d^* \quad 2s2$
 $r13^* \quad 1B14 \quad rv3^* \quad 2Bu4 \quad fa$

and closes contacts

30      $1b15^* \quad 2b15^* \quad 1bu5 \quad 2bu5 \quad 1b06 \quad 2b06$
 $1bu6^* \quad 2bu6^* \quad 1b11^* \quad 2b11^* \quad 1bu1^* \quad 2bu1^*$
 $1b02 \quad 2b02 \quad 1bu2 \quad 2bu2 \quad 1b03^* \quad 2b03^*$
 $1bu3^* \quad 2bu3^* \quad 1b14 \quad 2b14 \quad 1bu4^* \quad 2bu4^*$

which correspond to the digits 8, 0, 9, 6, 3, 5 (beginning with the units). These contacts are maintained in closed position by the polarization current, despite the breaking of the control current. The polarization current is shut off in the R group, the contacts defining the digits 0, 9, 6, 3, 5, 8 are open and a new elementary operation can begin.

Impulse diagram:

45   As has been said with reference to FIGS. 10 and 11, a current should be sent through fe and fa during the transfer phase, while the contacts ri or ri^* , as the case may be, are still closed. The contacts bi or bi^* , respectively, that then close should remain closed when contacts ri or ri^* , respectively, open to permit a new calculation phase. The attracted contacts of the B and R groups should therefore be kept in their positions in some way or other after the calculation and transfer phases are over. In the calculating machine that has been described, which is 55 equipped with relays that have at least three positions and electromagnetic polarization, holding the attracted contacts can be managed very conveniently by means of polarization windings. It is merely necessary to choose the ampere-turns of these polarization windings in such a 60 way that the excitation of these windings is not enough by itself to cause the attraction of an armoire, but yet enough to keep it in the drawn-up position.

FIG. 13 represents, as functions of the time, an impulse diagram that makes it possible to carry out a series of calculation and transfer phases while keeping the armatures of the R group in position during the transfer phase and those of the B group during the calculation phase.

At the initial moment of the diagram, it will be taken for granted that the contacts of the B group define a number and are held in position by a polarization impulse BP , the multiple-contact wipers of the A group being also so positioned as to define a number. The relays of the R group then receive a control impulse RM and a polarization impulse RP , which begin practically at the same time. At the end of impulse RM the contacts of the R group

have assumed their positions and are held there by the impulse RP, which is of longer duration than RM. Immediately after RM impulse ends, BP is interrupted and the contacts of the B group all come back to their rest positions. It is to be noted that opening of these contacts occurs when RM has come to an end, so that the current no longer passes across the contacts of the B group at this moment. While the contacts of the R group are held in their positions by polarization impulse RP, the relays of the B group receive a control impulse BM and a polarization impulse BP that begin practically at the same time. The contacts of the B group then assume positions that depend on the positions of the contacts of the R group. At the end of impulse BM, the contacts of the B group have assumed their positions and are held there by polarization impulse BP, which is of longer duration. After impulse BM is over, the contacts of the R group are no longer energized and impulse RP is interrupted, so that the contacts of the R group come back to their rest positions. The contacts of the B group are held in their positions by impulse BP while new impulses RM and RP begin. The cycle of impulses begins again, but this time their polarity is reversed. Impulses RM will therefore be alternately positive and negative, along with impulses RP; likewise for impulses BM and BP. This sort of alternation has no effect on the operation of the electrical apparatus, for it takes place at the same time in the control coils and the polarization coils of the relays. These changes of polarity are even helpful, for the interruptions between two successive polarization impulses, RP or BP as the case may be, can be cut short. For, if the impulses always had the same polarity, this interruption would have to be longer than the release time of the relays, in order to permit those armatures that are no longer used in the electrical groups to return to rest position. In the diagram shown, there occurs not merely an interruption of the current, but also a demagnetization phase that produces a forced release of the armatures. It is advisable to decrease the slope of the sides of these impulses, as shown in FIG. 13, by familiar methods, for example by condensers, in order to prevent the magnetic field from increasing too rapidly and reattracting the armatures before their complete release.

FIG. 14 schematically illustrates a collector commutator that makes it possible to deliver impulses according to the diagram of FIG. 13. The commutator has a current input portion X and two output conductors Y and Z that have been drawn side by side in FIG. 14 for clarity's sake, but that actually are placed coaxially one behind the other on a rotating shaft. The input part X has two current input brushes 111 and 110 in contact with two collector rings 108 and 109, which are connected to sectors 112, 113, 114, 115 of parts Y and Z. Polarization impulses RP and BP are collected on brushes 116, 117, 118 and 119 and control impulses on brushes 120, 121 and 122, 123. The commutator shaft is set in rotation by an electric motor.

We have said that the calculation operations could be performed by the machine by means of a series of two-phase elementary operations, that is, by an alternating series of calculation and transfer phases. FIG. 15 shows, in a very schematic way, how calculation and transfer circuits are fed by a generator Ig that delivers impulses RM, RP, BM and BP in conformity with the diagram of FIG. 13. In each denomination row the contacts of the B group are designated by BK_o, those of the A group by AK_o and those of the R group by RK_o. The control windings of relays R are designated by RM_a and those of the B group by BM_a. The polarization windings of the B and R groups are indicated as BP_o and RP_o, respectively. The contacts of the A, B and R groups and their control and polarization windings are shown for only the first two denomination rows of the machine, the other denomination rows being analogous. This diagram shows that at every calculation phase an impulse RM

passes in all the denomination rows of the machine successively, passing through contacts of the A and B groups and then through windings of the R group in each denomination row. At the same time, the polarization windings RP_o of the relays of the R group receive an impulse RP of longer duration than impulse RM, so that the contacts of the R group are held in their positions, while an impulse BM goes successively through the contacts RK_o of the R group and the windings BM_a of the B relays in each denomination row. In the same way, windings BP_o receive a polarization impulse BP of longer duration in order to maintain the contacts of the B group in their positions during the following RM impulse.

We have seen, in connection with FIGS. 10 and 11, that the various functions of the calculation and transfer circuits, that is, A+B addition with or without decimal shift, and transfer either direct or as a complement, could be ordered by the direction of the current during the calculation and transfer phases. The machine thus has a control mechanism that makes it possible to change the direction of the currents during the transfer and calculation phases, depending on the operation to be performed. This control mechanism is illustrated very schematically in FIG. 16. It comprises contacts SBK_o to control the direction of current during the calculation phase and contacts SRK_o to control the direction of the current during the transfer phase so as to produce the series of additions, denomination shifts and transfers, either direct or as complements, that are required to carry out the operations to be performed. A part at least of these contacts SBK_o or SRK_o, as the case may be, is controlled by relays with at least three positions, having control windings SRM_a or SBM_a and polarization windings SRP_o or SBP_o, as the case may be. The impulses RM and BM delivered by impulse generator Ig are sent to windings SRM_a and SBM_a, respectively, and then are fed into the calculation and transfer circuits by means of contacts SBK_o and SRK_o, which are designed to function as current reversers. Polarization impulses RP and BP go through polarization windings SRP_o, RP_o and SBP_o, BP_o, respectively. Impulse generator Ig is driven by a motor M_o. By means of a secondary shaft 99 this motor drives an electromagnetically controlled coupling K whose purpose is to drive certain mechanical appliances in the machine, such as a device for indicating the result, which makes number disks turn depending on the positions of the relays that define the result, or an arrangement for introducing the numbers, whose role is to situate the multiple contact wipers in a way dependent on the number read in on a keyboard or contained in a register. While the mechanical appliances are in motion, the impulse generator continues to be driven, but the impulses it delivers are shut off by relays of the control group, in order to suspend the electrical calculation operations.

Control portion of the calculating machine

FIGS. 17 to 20 represent the diagram of a control arrangement that makes it possible to bring about, on a planned program, the current reversals that are desired for a series of calculation and transfer phases. This control mechanism has relays assembled in two control groups B and R. These are three-position relays and act as two-pole switches. Three relays are provided in each group B and R, and are designated by the indices h, j, k. Each of the three relays of the B group comprises two control windings and three contacts for each of the positions I and II. The relays of the R group with indices h and j also have three positions and each of them comprises two control windings and three contacts for each of the positions I and II, while the relay with index k has two positions and comprises only one winding R_k and three contacts 1r_k, 2r_k, 3r_k, which are closed for one of the above positions and open for the other.

The circuit in FIG. 17 is connected by g to an output terminal of the impulse generator supplying impulses

RM, and by ge^* to input conductor ge^* of FIG. 19. Connections ge and ga of this drawing are connected to the input and output binding-posts of the calculation circuit according to FIG. 10. Finally, terminal ga^* is connected to the return binding-post of the impulse generator. The circuits according to FIGS. 18 and 20 are inserted in the same way between the transfer circuit of FIG. 11 and the terminals of the impulse generator that furnish impulses BM. The contacts shown in FIG. 19, which are controlled by the relays shown in FIG. 18, form part of contacts SRK_o , which were referred to in connection with FIG. 16, and the contacts shown in FIG. 20 form part of contacts SBK_o . The windings of relays Bh , Bj , Bk form part of windings SBM_a and those of relays Rh , Rj and Rk form part of the windings SRM_a shown in FIG. 16.

The fixed control mechanism illustrated makes it possible to perform six successive elementary operations.

To engage this control mechanism, winding $1Bh$ is energized, so that contacts $1bh$, $2bh$, $3bh$ are closed. These contacts are kept closed by a polarization impulse, and during the first calculating phase the current passes via g , $1Rh$, $1bh$, ge^* , $2bh$, ge (FIGS. 17 and 19) in circuit R according to FIG. 10 and leaves it by ga , $3bh$, ga^* . The contacts of the R group (FIG. 11) and contacts $1rh$, $2rh$, $3rh$ are closed. The direction of the current is "positive," for input conductor g is connected to calculation circuit input conductor ge and output conductor ga^* is connected to calculating circuit output conductor ga .

During the first transfer phase, output conductor fe^* of FIG. 18 is connected to fe^* of FIG. 20; fe of FIG. 20 is connected to fe of circuit B of FIG. 11; fa of the said circuit B is connected to fa of FIG. 20; the current output goes via fa^* . During the first transfer phase the current passes through f , $2Bh$, $1rh$, fe^* , $2rh$, fa in circuit B of FIG. 11 and leaves the latter by fe , $3rh$, fa^* . Contacts $1bh^*$, $2bh^*$ and $3bh^*$ are closed. We see that the current enters the B circuit by fa and leaves it by fe ; it goes in the opposite direction, that is, in the negative direction. The direction of the current in the polarization windings remains the same for all the phases, in the R group just as in the B group.

During the second calculation phase $1bh^*$, $2bh^*$, $3bh^*$ are closed, the direction of the current is negative, and $1rh^*$, $2rh^*$, $3rh^*$ are closed. During the second transfer phase the current is positive and $1bj$, $2bj$, $3bj$ are closed.

During the third calculation phase the direction of the current is positive and contacts $1rj$, $2rj$, $3rj$ are closed. During the third transfer phase the current is negative and $1bj^*$, $2bj^*$, $3bj^*$ are closed, and so forth up to the fifth operation.

The following table shows the sequence of these operations:

Calculating phase	operation	transfer phase	operation
1	+	1	-
2	+	2	+
3	+	3	-
4	+	4	-
5	-	5	+
6	+ special control		

The sixth calculation phase has, in addition to the normal control of the current polarity by $2bk^*$, $3bk^*$, a special operation, for example a read-out, by means of a supplementary contact $4bk^*$. This last may have already been made ready during the fifth transfer phase, if so desired. The table above shows that the sixth two-phase elementary operation is not complete, since it has only a calculation phase. This is the reason why the k index relay of group R has only one control winding and only a set of three contacts for one switching position. It is clear that if the sixth calculation phase had to be followed by a sixth transfer phase, the latter

70

75

could be ordered by replacing relay k by a relay with two windings and three positions, analogous to the h and j index relays.

It is obvious that any sequence of positive and negative currents, in any number, can be obtained by choosing the number of relays and of the contacts they control. The operation described, by means of elements with the three positions, 0, I, II, has the advantage over a series of operations by means of normal relays that the number of relays required may be divided by $Q-1$ (Q =number of positions). On the same principle it would also be possible to work out a cyclical calculation plan of this sort and have it repeat itself several times beginning with the first relay, every time a certain relay was excited. Different fixed controls on the diagram described are obtained with different sequences of positive and negative currents, and in these cases it is possible that during the calculation phase the current input should take place through $ge1$, ga instead of ge , ga (FIG. 10) (addition of a 1 in the first decimal place of the machine).

It is also possible to feed the current in via $f0e$ and $f0a$ during the transfer phase instead of fe and fa , in circuit B of FIG. 11 (introduction of a 0 or a 9 in every 25 decimal place of the machine).

In the circuits of FIGS. 17 to 20, windings $1Rh$ to Rk or $1Bh$ to $2Bk$ can be placed directly in the predetermined control circuits of FIGS. 19 and 20, thus eliminating contacts $1bh$ to $1bk^*$ or $1rh$ to $1rk$, respectively. For example, $1Rh$ is directly connected before or after $2bh$ (or $3bh$) and the same for the other windings of the circuits of FIGS. 17 and 18.

Means for controlling a fixed program, of the nature of the one described above, are used in the calculating 35 machine to carry out certain operations such as addition, subtraction, shifting a certain number of places to the left or the right, deleting the result, etc.

To perform automatic multiplication and division, this control mechanism must take into account numbers that appear in the course of the operation. It is thus necessary in this case to provide supplementary contacts on certain relays of the B and R groups, these contacts being provided in order to energize relays of the control mechanism to perform the operations made necessary by the appearance of certain numbers in the course of the calculation operation.

Instead of providing an impulse generator furnishing impulses with alternating polarity, it is quite possible to envisage the use of impulses that always keep the same 50 polarity. FIG. 21 gives a diagram of constant polarity impulses, which can without further ado replace the impulses of the diagram as in FIG. 13. FIG. 22 represents the scheme of an impulse generator furnishing impulses according to the diagram of FIG. 21.

The principal part of this generator is a vibrator with a system of contacts made up in a way well-known to the industry, with three contacts C1, C2 and C3 vibrating between two fixed poles that tend to draw the armature to its two extreme positions alternately, to the rhythm of the vibrating tongue. FIG. 23 schematically represents the construction of such a vibrator. It has a tongue 150 bearing a movable contact 151 designed to cooperate with fixed contacts 152 and 153. Electromagnets 154 and 155 are designed to attract in alternation an armature 156 attached at the end of tongue 150.

In addition to the vibrator, the circuit of FIG. 22 contains two auxiliary relays E1 and E2, a starting relay H and resistances $r1$ and $r2$. The drawing also shows the electrical assemblies fed by the impulse generator: AK_o BK_o RM_a RP_o RK_o BM_a BP_o , with the assemblies of the control portion (not shown in FIG. 22).

The operation of the impulse generator is as follows: if a suitable source of direct current is connected at points G1 and G2, electromagnet 154 has a strong impulse pass

through it at once, for it is actuated by the total voltage, by means of rest contact h of starting relay H . At the same time 155 and BPo receive a considerably feebler impulse through $r2$. The vibrator armature is drawn to the extreme position on the side of electromagnet 154, which is strongly excited, and closes the upper contacts of $C1$, $C2$, and $C3$. At the same time a current goes through delayed-action relay H , which opens rest contact h when the vibrator armature has made its lateral shift, and starts the oscillations of the vibrator. The latter's electromagnets 154 and 155 now receive impulses through resistances $r1$ or $r2$ and polarization windings RPo or BPo , respectively, impulses that are much feebler than the initial impulse, since maintaining the armature's oscillations from one of its extreme positions to the other requires much less force than shifting to one of its extreme positions, starting from its rest position.

While the upper contact of $C1$ is closed and h is open, electromagnet 154 is without current and the vibrator starts in the opposite direction. At the moment that $C1$ closes $E1$ is energized and $e1$ is closed, since the time during which $E1$ is attracted is less than the duration of the current impulses that the vibrator can supply. At the same time, circuits for the current are set up through RPo , BPo , RKo — BMa , and at the return of the vibrator armature the circuits through BPo and RKo — BMa are broken, while circuit RPo is not broken, as contact $e1$ remains closed.

At the same time electromagnet 155 becomes operative. Closing the lower contacts of $C1$ to $C3$ sets up circuits through RPo , BPo , AKo — BKo — RMa ; $E2$ is excited; $e2$ is closed, since the time during which $E1$ is attracted is less than the time of the vibrator's current impulses; the coil of $E1$ is short-circuited so that $e1$ is open (time of release of $E1$ and $E2$ shorter than time of vibrator impulses). When the lower contacts of $C1$ to $C3$ are open, the circuits through RPo and AKo — BKo — RMa are broken, but not the one through BPo , as contact $e2$ is closed. Thereafter, the set of operations described is repeated until the circuit through $G1$ and $G2$ is broken or one of the two contacts $p1$ and $p2$ is closed. In the second case, one of electromagnets 154 or 155 is subject to a strong and long impulse, which keeps the armature of the vibrator indefinitely in one of its extreme positions. When $p1$ or $p2$, as the case may be, is open again, the sequence of impulses begins its normal rhythm again. Closure of contact $p1$ or $p2$ is aimed at interrupting the sequence of impulses for a certain time, while retaining the numbers that are in the B group or the R group, in order to allow the performance of relatively slow operations, such as the introduction of a number into the contacts of the A group or the exploration of the positions of the relays defining the result by a read-out mechanism. Contacts $p1$ and $p2$ are controlled by relays of a control circuit; it is important that these contacts be engaged in correct phase with the vibrations of the vibrator tongue.

The diagrams of calculation and transfer circuits shown in FIGS. 10 and 11 were drawn up for a machine having a total of six columns, in order to simplify the drawings, but it is understood that the number of columns in a machine may be chosen in any way whatsoever. Moreover, each decimal place was designed to define ten digits and thus make it possible to carry out operation on the decimal system, but it is clear that machines could be constructed to perform operations on different systems, such as machines to calculate times in hours, minutes and seconds or accounting machines for non-decimal monetary systems. It will be seen that in the present description the term "denomination row" has been used in a very broad sense, comprising among others the case where the number of digits definable in an order is different from ten.

The machine can have a keyboard acting directly on contacts A to introduce numbers into the A group, but the contacts of group A can also be operated by relays. 75

In that case, the use of multi-position polarized relays of the kind described hereinbefore is advisable, as they make it easily possible to hold the armatures in place. Of course, any other kind of relay, with or without means for holding the armatures in their positions, could be used, as the actuation time does not play an important part when no engagement of the A group is to occur during the calculation. The use of electromagnetic relays is of particular advantage when the introduction of a number into the A group is done not only through a keyboard but also through registers or perforated cards. A keyboard can be provided at the same time and have contacts to make it possible to control the said relays in the familiar manner.

FIG. 24 represents the calculation circuit of a machine according to a second embodiment, with four denomination places and in which the numbers are defined on the decimal system.

FIG. 25 illustrates the corresponding transfer circuit.

FIG. 26 shows in detail the contacts and windings of the relays of one denomination place of the B group.

This machine works on the decimal system and its keyboard shows four denomination rows, that is, the same number as the R group. The calculation circuit of FIG. 24 is analogous to the circuit represented in FIG. 10 for the first embodiment. Each denomination row of this group comprises two input and two output conductors, making a ten's carry possible. The first denomination row has two input conductors ge and $ge1$, connected to ten double contacts $1b0$, $2b0$, $1b1$, $2b1$, $1b2$, $2b2$, $1b3$, $2b3$, $1b4$, $2b4$, $1b4^*$, $2b4^*$, $1b3^*$, $2b3^*$, $1b2^*$, $2b2^*$, $1b1^*$, $2b1^*$, $1b0^*$ and $2b0^*$, corresponding by pairs to the digits 0, 1, 2 . . . 8, 9 respectively. These double contacts belong to the B group and are connected to eleven movable points of a ten-position multiple wiper of the A group. This wiper has twenty fixed points that are connected to twenty windings, the first ten of which $1r0$, $1R1$ . . . $1R8$, $1R9$, are connected to the first of the said output conductors, the second winding group $2R0$, $2R1$ . . . $2R8$, $2R9$ being connected to the second output.

The principle of the connections is the same as for FIG. 10, and when a current impulse is sent through ge , the current goes through that winding of the R group that defines the number corresponding to the addition of the numbers defined by the contacts of the B group and by the position of the multiple-contact wiper of the A group.

In the circuit according to FIG. 24, the different denomination rows are connected in series in order to make possible the ten's carry at the same time as the calculation phase. The circuit has two input conductors ge and $ge1$ and one output conductor ga . The normal input is ge ; when the current comes in through $ge1$, we have the supplementary addition of a 1 in the first denomination row. This input can be used to count the number of elementary two-phase operations in combined operations or to convert a nine's complement into a ten's complement. The direction of the current that is sent through ge or $ge1$ and ga determines whether contacts ri or ri^* of FIG. 25 should be closed during the calculation phase. A warning device L may be provided to give warning when the capacity of the machine is being exceeded during a calculation, a device that may be used for non-automatic division, for example. In machines with a mechanism for automatic division, the warning device should be replaced by a relay of the control mechanism.

FIG. 25 represents circuit B. The current input takes place at fe and the output at fa , or vice versa. A current impulse produces the transfer of the result of the previous calculation, held over in contacts ri or ri^* to contacts bi or bi^* respectively of FIG. 24.

As is seen from FIG. 25, a transfer occurs in the same denomination row when the contacts of group ri are closed, and a transfer takes place in the following col-

umn when the contacts of group ri^* are closed. This transfer circuit is not provided for in cyclical denominational shifts, as in FIG. 11. When a shift in denominational row occurs, the digit in the four denominational row disappears, for this denominational row has no ri^* contacts, while a zero is introduced in the first denominational row. The introduction of this zero is obtained by means of a relay with a winding D, connected just before output ga of the calculation circuit of FIG. 24, and of contacts $1d$, $1d^*$ and $2d^*$.

When a calculation phase is performed with a current of positive polarity, contact $1d$ is closed, while contacts $1d^*$ and $2d^*$ are open, and the following transfer occurs without a denominational shift. When, however, a calculation phase is performed with a current that is negative in polarity, contacts $1d^*$ and $2d^*$ are closed instead of $1d$ and the transfer occurs with a denominational shift, contact $1d^*$ causing the current to pass through winding $1B0$ of the first denominational row to introduce a zero in that column.

As in the first embodiment, the direction of the current during the transfer phase makes it possible to carry over into the B group the number defined in the R group, or its nine's complement.

FIG. 26 shows the relays B of a denominational row and their contacts, in order to show how the formation of the complementary value is obtained. Each denominational row has five three-position electromagnetically polarized relays, with a double contact for each switching position. The digits of an order of ten are defined by the closure of the following contacts:

1b0	2b0	0
1b1	2b1	1
1b2	2b2	2
1b3	2b3	3
1b4	2b4	4
1b4*	2b4*	5
1b3*	2b3*	6
1b2*	2b2*	7
1b1*	2b1*	8
1b0*	2b0*	9

It appears from this arrangement that reversing the direction of the current causes contacts bi to close instead of bi^* , and vice versa, which produces the formation of the nine's complement. Moreover, each relay has two windings $1Bi$, $2Bi$, with windings in opposite directions. These windings are connected with contacts ri and ri^* and are provided for the formation of complementary numbers.

As is shown in FIGS. 25 and 26, the relays of the B group that correspond to the number 0 are equipped with a supplementary winding $3B0$. These windings make it possible, depending on the direction of the current, to introduce a 0 or a 9 into all the denominational rows. In the embodiment that has been described, these windings become operative at the beginning of each new calculation operation in connection with the mechanical operation of introducing the numbers.

The positions of the contacts of the circuits illustrated in FIGS. 24 and 25 correspond to the operation:

$$3534 + 1382 = 4916$$

$$4916 \rightarrow 5083$$

The positions of the multiple-contact wipers correspond to the number 3534 and those of the contacts of the B group to the number 1382. The transfer is to be made without a denominational shift, so that the direction of the current impulse RM should be positive during the calculation phase. The current is fed in through ge (FIG. 24). The direction of the current will be negative, however, during the transfer phase, since the result of the addition is to be changed into its nine's complement; the current will therefore enter at fa .

It will be observed, further, that during the transfer

phase the current does not pass through the denominational rows in their numerical order. In fact, the various denominational rows may be connected in any order so far as the passage of the current is concerned, since there is never a ten's carry during the transfer. It is enough that the direction of the current should be the same in all the denominational rows.

FIGS. 27 to 29 refer to a variant whose chief difference from the first two embodiments is the fact that the multiple-contact wipers are eliminated and replaced by contacts forming a table of addition, and that the numbers are defined on a system known as odd-even.

FIG. 27 schematically represents the calculation circuit.

FIG. 28 represents the transfer circuit.

FIG. 29 shows the principle of the formation of the complement.

FIG. 30 shows a form of construction of the keyboard contacts.

Using the odd-even system makes it possible to define 20 the ten digits of a denominational row by means of seven switching elements; we see that this number of elements is the same as for the biinary system. These seven elements are divided into two groups: the first comprises two switching elements (u , v) that make it possible to determine whether the number is odd or even, and the second group has five elements corresponding to the digits 0, 2, 4, 6, 8. Representation of the digits of an order of ten is thus performed according to the following table:

	Number	element 1	element 2
0		u	0
1		v	1
2		u	2
3		v	2
4		u	4
5		v	4
6		u	6
7		v	6
8		u	8
9		v	8

The diagram of the calculation circuit represented in FIG. 27 is analogous to that of FIG. 10, with the exception of the use of the odd-even system and the replacement of the multiple-contact wipers by sets of contacts (table of addition). This variant embodiment presents six denominational rows, of which only three have contacts of the A group, in a completely analogous manner to the first embodiment. The input conductors ge or $ge1$ again correspond to an input with or without addition of 50 a 1 in the first denominational row, respectively.

In each denominational row of the group R there are seven read-out relays according to FIGS. 4 and 5 with polarization windings in common, in which the armatures are used directly to indicate the result. Every relay of

55 the R group in the first three denominational rows has two control coils $1Ri$, $2Ri$ and two single working contacts ri and ri^* , corresponding to positions I and II respectively, as defined in connection with FIG. 3. Group B comprises four relays in each denominational row, which make 60 it possible to form the complement by reversing the direction of the current. Each of these relays has two or three windings $1Bi$, $2Bi$, $3Bi$ and a double working contact $1bi$, $2bi$ or $1bi^*$, $2bi^*$ for each of the positions I and II, respectively.

65 In each of the first three denominational rows the A group has five sextuplet contacts $a0$, $a2$, $a4$, $a6$, $a8$ as well as a triple reversing contact au — av , each of the sextuplet contacts corresponding to two successive digits of a denominational row. These contacts are actuated directly by 70 the keys of the keyboard.

FIG. 30 shows the principle of the coupling of the keys with the contacts of the A group. Each denominational row of the keyboard has ten keys corresponding to the digits from zero to 9, respectively. Only the keys 75 corresponding to zero and one have been shown in FIG.

30. Each group of two consecutive keys 0-1, 2-3, 4-5, 6-7, 8-9 acts on a sextuple contact a_0 , a_2 , a_4 , a_6 , a_8 , respectively (FIG. 27). FIG. 30 shows the two keys 0 and 1, which can act on the corresponding sextuple contact a_0 by means of a bent lever 100 made of an angle iron. Triple reversal contact $au-av$ is actuated by a bent lever 101 also in the form of an angle iron, which can be actuated by any of the keys corresponding to an odd number. By these simple measures of construction, it is possible to have the number struck on the decimal keyboard converted into the odd-even system.

Moreover, it is advisable to have levers 100, 101 change the relatively large displacement of the keys of the keyboard into a relatively short movement of the contacts, so that despite the large number of contacts the action pressure of the keys can be kept low enough.

The sets of contacts of the A group are designated on the same principle as the contacts of the R group, of course replacing the letter r by the letter a , but the sets of sextuple or triple relays are designated as a unit, while in the R and B groups, each contact is designated separately.

Circuit B of FIG. 28 is analogous to that of FIG. 11, details excepted, and differs from it first in the element-number correspondence, which is determined by the odd-even system, and then by new wiper contacts $2ri$ and $2ru$, with five and two switching positions respectively and one rest position, which are connected in parallel to contacts ri and ru , respectively. During the electrical calculation operations, they are in the position illustrated in FIG. 28 and have no effect on the calculation. These contacts are controlled by a read-out mechanism so as to make it possible to introduce the number set up in this indicator into the B group.

Finally, FIG. 29 represents the arrangement of contacts and windings in the B group, with an arrangement allowing the formation of the complement in a simple way by reversal of the current. FIG. 29 is analogous to FIG. 12, but the correspondence between contacts and numbers is changed because of the use of the odd-even system. This correspondence follows the pattern:

1b0	2b0	1bu	2bu	0
1b0	2b0	1bu*	2bu*	1
1b2	2b2	1bu	2bu	2
1b2	2b2	1bu*	2bu*	3
1b4 (1b4*)	2b4(2b4*)	1bu	2bu	4
1b4 (1b4*)	2b4(2b4*)	1bu*	2bu*	5
1b2*	2b2*	1bu	2bu	6
1b2*	2b2*	1bu*	2bu*	7
1b0*	2b0*	1bu	2bu	8
1b0*	2b0*	1bu*	2bu*	9

It will be noted that a reversal of the direction of the current causes a reversal of contacts $1bi$, $2bi$ with $1bi^*$, $2bi^*$ (and vice versa), which makes it possible to get the formation of the nine's complement.

Switch $1s_2$, $2s_2$ of FIG. 28 makes it possible to break the cyclical denomination shift between the third and fourth decimal rows as in FIG. 11. Contact d or d^* , as the case may be, is controlled by a relay D, depending on the direction of the current, and makes it possible to define the path of the current in FIG. 28, according as the transfer is to take place with or without a shift of a decimal place.

The positions of the contacts of the circuits illustrated in FIGS. 27 and 28 correspond to the operation:

$$872 + 715518 = 716390$$

$$716390 \rightarrow 163907$$

The positions of the sextuple contacts and triple reversal contacts of the A group correspond to the number 872, and the positions of the contacts of the B group to the number 715518. The transfer must be made with a cyclical decimal shift, so that the direction of impulse RM must be negative during the calculation phase. The

current is fed in at ga and leaves at ge (FIG. 27). The direction of the current is positive during the transfer phase, since a conversion to the complement is not desired.

Use of the odd-even system is equivalent to the use of the biquinary system so far as the number of relays and contacts required is concerned. A certain resemblance will therefore be noted between the electrical groups in embodiments 1 and 3, especially when those circuits are compared in the two systems in which the A group is equipped with multiple-contact wipers or tables of addition. As a supplement, FIG. 31 shows the calculation circuit on the even-odd system for one decimal place, in which multiple-contact wipers (as in FIG. 10) are used instead of a table of addition. Comparison with the circuit in FIG. 10 shows the equivalence of the means used. Embodiment 1 can therefore be converted for the odd-even system by a few simple modifications. Further, FIG. 32 represents a decimal place of the biquinary system in which a table of addition has been used. It is obviously possible to use such a diagram in the first form of embodiment, but this leads to constructive solutions that are inconvenient for the integration of keyboard and group A contacts, since use of the odd-even system presents certain advantages with respect to the keyboard arrangement, because of the equivalence of the adjacent digits 0-1, 2-3, etc. When the A group is equipped with electromagnetic relays, these advantages no longer apply and the two systems are equivalent as to the equipment used.

The multiple-contact wipers provided in the second embodiment could also be replaced by sets of contacts forming a table of addition. The connection between the contacts of the A and B groups and the windings of the R group need not necessarily be of such a kind that the result of a calculation phase is the addition of the numbers defined in the A and B groups, for the equipment used in the construction of a machine and the rapidity of its calculations would hardly be altered if this addition were replaced by a subtraction.

The elementary operations needed to perform an arithmetical operation may be selected in such a way as to define the result of this operation either by the relays of the R group or by those of the B group. The value of this result can be shown by means of a read-out mechanism that can explore the positions of the relays defining the result and actuate a read-out device in accordance with the positions encountered.

The machine described was equipped with three-position relays in the B and R groups, but elements with more than three positions may be used without introducing many changes in the transfer and calculation circuits. FIGS. 8 and 9 represent a set of relays with five positions each, which can be selected by means of the corresponding connections of the polarization windings. These elements can be used to advantage in more complicated electrical machines, such as bookkeeping machines, machines for perforated cards and machines controlled by a predetermined program, etc., for they make it possible to obtain a large number of connections, which simplifies the combination of several calculation groups into a single unit. Thus, replacing three-position elements in the R group of one of the calculation circuits described above by five-position elements would make it possible to have four transfer possibilities instead of two. In the example described, these possibilities comprised:

(1) Making ready the transfer to the B group in the same decimal place.

(2) Making ready the transfer to the B group in the next denomination row to the left.

When relays as in FIG. 8 are used, these two possibilities can be retained, for example, while the two other possibilities may be utilized to make ready the transfer to an electrical indicator, to a printing indicator, to a register, to the B group of a calculation bloc connected

in parallel, etc. One of these possibilities may also be utilized for tabulation to the right. Simultaneous switching to several positions can be obtained by suitable connection of the polarization coils as in FIG. 8; this makes it possible to perform several transfer operations at once.

Obviously, in the case of a calculating machine intended solely for addition and subtraction, the denomination shift could be eliminated, so that the relays of each decimal place of the R group could define numbers in the same way as the relays of the B group. In this way the number of relays of the R group could be cut almost in half.

One of the characteristics of relay calculating machines lies in the representation of denomination rows, which may be "parallel" or in series." The embodiments that have been described are all of the "in parallel" type, that is, a single set of calculating elements is provided for each denomination row. Such an arrangement, it is well known, has the advantage of allowing a calculation time as short as possible for a given time constant of the switching elements. Nevertheless, it is possible without further ado to use the diagrams that have been referred to in the description for machines "in series," which in general have calculation circuits for a single denomination row, the successive numbers of a calculation being put into this place one after the other in order to perform the calculation. In this case a register has to be provided to hold the numbers that are not used, this register taking the form of such well-known devices as perforated bands, magnetic recording tapes, etc.

The procedure by which a machine in parallel is changed into a machine in series is well known and will therefore not be described in detail. In any case, machines in series have the drawback of being relatively slow.

I claim:

1. An electric calculating machine operated by current impulses, comprising at least a first, a second and a third group of contacts, operating elements for said contacts, the first group being for the purpose of introducing into the machine the numbers constituting the operands of an arithmetical operation, the contacts of this first group being connected to the contacts of the second group and to said operating elements of the contacts of the third group so as to cause the contacts of this third group to assume a position determining the number corresponding to the result of an operation performed involving two other numbers determined by the contact closing positions of the first and of the second group, respectively when an impulse is sent into the contacts of the said first and second groups; the contacts of at least one of the three groups being operated by three-position, polarized relays, one of these positions being a rest position, the two others being working positions in which selected ones of said contacts are closed; said relays having polarized windings and relay control windings, the contacts operated by the said three-position relays thereby defining different numbers according to whether the relays occupy the one or the other of their working positions; a group of control members being connectable to the polarized windings or to said relay-control windings provided to cause the polarized relays to assume the one or the other of their working positions according to the arithmetical operation of addition, subtraction, multiplication or division to be carried out.

2. A calculating machine according to claim 1, wherein the relays each include an armature carrying said contacts and having electromagnetic polarization, the ampere-turns of the said control and polarization windings of these relays being chosen in such a way, depending on the magnetic circuit of these relays, that the excitation of the polarization windings is insufficient to cause the attraction of said armature carrying said contacts, but sufficient to maintain said armature in an attracted position.

3. A calculating machine according to claim 2, wherein the said ampere-turns are chosen in such a way that when the effect of a polarization winding is opposed to that of a control winding, the resultant magnetic field is not enough to cause the attraction of an armature subjected to this field for a working position.

4. A calculating machine according to claim 1, said armature carrying contacts comprising first, second and third groups of switching elements with contacts controlled by said respective relays, the control windings of the relays of the third group being connected in series to the contacts of the first and second groups to form a calculation circuit, means being provided to have an electrical current impulse pass across the closed contacts of the first and second groups to cause the attraction of certain of said contact carrying armatures of the relays of the third group, whereby the closing of the contacts of this group are adapted to define the number corresponding to the result of a simple operation performed with the two numbers represented by the closed contacts of the first and second groups.

5. A calculating machine according to claim 4 wherein the control windings of the relays of the second group are connected in series to the said switching contacts of the third group to form a transfer circuit, means being provided to have a current impulse pass across the closed contacts of the third group to cause the attraction of corresponding contact carrying armatures of the relays of the second group, whereby the said corresponding contacts of said second group, by their closure, define a number depending on the one defined by the closed positions of the contacts of the third group.

6. A calculating machine according to claim 5, wherein said means to provide a current impulse is adapted to supply a first series of control impulses to said control windings and polarization impulses to said polarization windings to actuate the armatures of the third group, each polarization impulse being of longer duration than a control impulse, in such a way as to maintain in their positions those armatures of the relays of the third group that have been attracted, the said current impulse means furnishing a second series of control impulses and polarization impulses, said impulses being out of phase in time with the first series of impulses, each second series of polarization impulses being of longer duration than a respective second series of control impulses to thereby hold said armatures of the relays of the second group in attracted position.

7. A calculating machine according to claim 6, wherein the said means to provide a current impulse is adapted to furnish said first series of control impulses to said control windings and second series of control impulses to said control windings, each of the second series following an impulse of the first series, the current impulse means also furnishing a first series of polarization impulses to said polarization windings, each of which begins at the same time as a first series control impulse and ends after the following second control impulse, and a second series of polarization impulses to said polarization windings, each of which begins at the same time as a second series control impulse and ends after the following control impulse of the first series.

8. A calculating machine according to claim 7, wherein in the relays of the third group are polarized relays with at least three positions, of which one working position is adapted to form a transfer circuit to transfer the digit defined in the third group to the same decimal place of the second group, the other working position being adapted to transfer this digit to one of the adjacent decimal places.

9. A calculating machine according to claim 8, wherein contacts and connections are provided in the transfer circuit so that when there is a decimal shift in one direction, the digit in the last decimal place in that direction can be transferred to the extreme opposite decimal place.

10. A calculating machine according to claim 7, wherein in the impulse generator is adapted to furnish impulses whose polarity varies in alternation, so that the magnetic fields of the relays pass through the value zero and are thus adapted to decrease the time during which the current is broken between two successive impulses.

11. A calculating machine according to claim 5 wherein in the relays of each denomination row of at least one of the second or third groups are polarized relays with at least three positions, of which one working position is adapted to define a digit and the other working position is adapted to define another digit, the number of relays provided in each denomination row of the said group being equal to half the number of positions required to define all the digits of a decimal place, rounded off to the next higher whole number.

12. A calculating machine according to claim 11 wherein the relays of the said second group of relay switching elements are polarized and have at least three positions, of which one working position is designed to define a digit and the other working position is designed to define the nine's complement of this digit, to thereby convert a digit, defined by a relay, into its complement by reversing the direction of a current impulse acting on that relay.

13. A calculating machine according to claim 12, wherein means are provided for reversing the polarity of the impulse passing through the control windings of the relays of the second group, in order to transfer the number of the third group as its nine's complement into the second group, said contacts of said switching elements of the third group being connected to the relays of the second group.

14. A calculating machine according to claim 12, wherein means are provided for reversing the polarity of the polarization current of the relays of the second group, in order to make it possible to transfer the number of the third group as its nine's complement into the second group, said contacts of said switching elements of the second group being connected to the relays of the third group.

15. A calculating machine according to claim 4 wherein in the different switching positions of the relays of the third and second groups are adapted for the transfer of definite numbers from the second to the third group by the positions of their contacts in various combinations.

16. A calculating machine according to claim 8, wherein in the said means for providing impulses consists of a vibrator with at least one vibrating tongue, a pair of electromagnets for motivating the same, said electromagnets being set close to the extreme positions of the said tongue, contacts actuated by said tongue furnishing three series of double impulses, one of these double impulses furnishing the said first and second series of control impulses to said control windings while for each of the two other double impulses, the two partial impulses forming a double impulse are combined periodically to form the polarization impulses to said polarization windings.

17. A calculating machine according to claim 16, wherein there is included a pair of relays, said pair of relays are adapted to join said partial impulses periodically with each other upon closing the contacts of said respective relays.

18. A calculating machine according to claim 17, wherein relay means including contacts in shunt connection with a pair of associated resistance and windings, respectively, are provided for applying at will a strong exciting voltage to one or the other of the said electromagnets that excite the vibrating tongue, in order to lock said tongue in one of its extreme positions and said contacts actuated thereby to closed position sending a long-lasting polarization impulse through the polarization winding of the second or third relays of the switching element groups.

19. A calculating machine according to claim 18, wherein the windings of said electromagnets are each connected in series to a first and second resistance, the contact of one of said respective relay means being adapted to shunt one of these resistances in its rest position, the winding of said relay being excited without interruption during the operation of the vibrator, and when the vibrator is not excited, said contact is closed, whereby the complete voltage is applied to the vibrator, so that said first impulse of current in one of the electromagnets is stronger than the following impulses.

20. A calculating machine according to claim 1, wherein contacts of the first and second groups are connected to the said control windings of the relays of the third group whereby the positions assumed by the contacts of the third group under the influence of an electrical control impulse in the relay control windings thereof define the number corresponding to the sum of the numbers set up in the contacts of the first and second groups, while the connections between the said control windings of the second group and the corresponding contacts of the third group are established whereby a second control impulse therethrough can impart to the contacts of the second group positions indicating the same number as the one defined by the positions of the contacts of the third group by energization of the control windings of said second group corresponding to said contacts of said third group.

21. A calculating machine according to claim 20, wherein each decimal place of the calculation circuit comprises two input conductors and two output conductors, a set of double contacts actuated by the relays of the second group, the relays of the second group acting on said double contacts, the contacts of the first group being connected to the contacts of the second group and to the windings of the relays of the third group, each relay of the third group comprising two main windings, the first input conductor being connected to said relays and being used for the simple addition of the numbers defined by the contacts of the first and second groups of the said decimal place, the second input conductor being connected to said relays and adapted to perform the same operation with the supplementary addition of a 1, the two output conductors being connected with the relays and to the two input conductors of the next higher decimal place, whereby the current passes through one or the other of the two windings of a relay of the third group to selectively bring about the addition of a 1 in the next higher decimal place digit.

22. A calculating machine according to claim 21, wherein each decimal place the first group comprises a multiple-contact wiper, the second group comprises ten double contacts and the third group ten relays, each bearing two main windings forming two groups, the windings of the first group being connected to one of the said output conductors and adapted to define numbers less than ten, while the windings of the second group are connected to the other said output conductor and adapted to define the numbers from 10 to 19, the multiple-contact wiper comprising twenty fixed contact points, each point being connected to one terminal of the said windings of the relays of the third group, and eleven movable contact points connected to the two input conductors by contacts of the second group.

23. A calculating machine according to claim 21, wherein each decimal place of the calculation circuit is composed of two portions, each comprising two input conductors and two output conductors, connected to said relays of said respective groups, the said second group of the first portion comprising five double contacts, the contacts being connected to the two output conductors of the preceding decimal place and to six movable points of a multiple-contact wiper of the first group, the said six movable points being adapted to assume five different positions with respect to ten fixed points, which are con-

nected to one of the terminals of ten main windings of five relays of the said third group, each of said five relays bearing two windings, the other two terminals of these windings being connected to two output conductors, respectively, of this first portion, the second group of the second portion comprising two double contacts connected to the two output conductors of the first portion and to three movable points of a two-position multiple-contact wiper of the first group, these three movable points being displaceable with respect to four fixed points connected to one of the terminals of four windings of two other relays of the third group, the other terminals of these windings being connected to the two said outputs, respectively, of the second portion, the five-position multiple-contact wiper being adapted to define the digits from 0 to 4 for one position of the two-position wiper and from 5 to 9 for the other position of the said two-position wiper.

24. A calculating machine according to claim 21, wherein each decimal place of the calculation circuit is composed of two portions, each comprising two input conductors and two output conductors, connected to said relays of said respective groups, the second group of the first portion comprising two double contacts connected to two output conductors of the preceding decimal place and to three movable points of a multiple-contact wiper of the first group, these three movable points being adapted to assume two different positions with respect to four fixed points, which are (each) connected to a terminal of four windings of two relays of the third group, the other terminals of these windings being connected to two output conductors, respectively, of this first portion, the second group of the second portion comprising five double contacts, connected to the two output conductors of the first portion and to six movable points of a multiple-contact wiper of the first group, these six movable points being adapted to assume five different positions with respect to ten fixed points, these last being connected each to a terminal of ten windings of five relays of the third group, each of these relays bearing two windings, the other terminals of these windings being connected to the two said output conductors, respectively, of the second portion, the multiple-contact five-position wiper being adapted to define the even digits from 0 to 8 for one position of the two-position wiper and the odd numbers from 1 to 9 for the other position of the said two-position wiper.

25. An electric calculating machine operated by current impulses, comprising at least a first, a second and a third group of contacts, operating elements for said contacts, the first group being for the purpose of introducing into the machine the numbers constituting the operands of an arithmetical operation, the contacts of said first group being electrically connected to the contacts of said second group and to said operating elements of the contacts of the third group, whereby the contacts of the third group are forced to assume a position determining the number corresponding to the result of an arithmetical operation, such as addition or the like, involving two other numbers determined by the contact closing positions of the said first and of the said second groups, respectively, when an impulse is transmitted into said contacts of said first and second groups, the contacts of at least one of

the three groups being operated by three-position polarized relays having movable armatures, one position being a rest position and the others being working positions in which selected ones of said contacts are closed, said relays having polarized windings and control windings, the contacts actuated by the said three-position relays thereby defining different numbers according to the working position of said relays, a group of control numbers being connectable to the polarized windings or to said relay control windings, to thereby actuate the said polarized relays to one or the other of their respective working positions for addition, subtraction, multiplication or division, said armature carrying said contacts in the provision of switching elements comprising the said first, second and third groups of contacts, the control windings of the said relays of the third group of contacts being connected in series with the contacts of the first and second groups in the provision of a calculation circuit, electrical impulse generating means across the closed contacts of the first and second switch groups causing attraction of certain armatures of the relays of the third switch group, whereby the resultant closing of the contacts of said third group are adapted to define the number corresponding to the result of a simple relay operation for two numbers represented by the closed contacts of the said first and second switch groups, said control windings of the said relays of the second switch group being connected in series with the said switching contacts of the said third switch group in the provision of a transfer circuit, electrical impulse generating means across the closed contacts of the third switch group to cause attraction of certain of said contact carrying armatures of the said relays of the second switch group, whereby the contacts of said second switch group upon closing define a number depending on the one defined by the closed positions of the contacts of the third switch group, the said arithmetical operations being key controlled, said keys including means acting on multiple contact relays to provide functioning thereof in successive predetermined order, each of said multiple contact relays controlling at least one double two-position contact, and multiple contact relays controlled by said keys in circuit connection with the contacts of said second and third switch groups, said last-mentioned relays controlling double contacts movable to a position to reverse the polarity of electrical impulses from said impulse generating means according to the digits defined in said second and third groups to perform an arithmetical operation.
